UNITED STATES PATENT OFFICE.

EARL H. ROLLINSON, OF LYONS FARMS, NEW JERSEY, ASSIGNOR TO COOPER HEWITT ELECTRIC COMPANY, OF HOBOKEN, NEW JERSEY, A CORPORATION OF NEW JERSEY.

LAMP-BULB SOCKET.

Application filed November 25, 1922. Serial No. 603,186.

My present invention relates to means for overcoming the difficulties experienced in the use of the usual form of sockets in which rectifier bulbs of the incandescent cathode or kenetron type are mounted, and more particularly to the means employed to prevent the melting or fusing of the bulb contacts at the point where connection is made with the spring lead in the bottom of the 10 socket. While the improved socket is designed particularly for use with rectifier bulbs, yet its construction is such that it is admirably adapted for use with any incandescent lamp bulb.

15 In the accompanying drawing forming a part of this specification,

Fig. 1 is a plan view of my improved socket.

Fig. 2 is a side elevation of the same.

20 Fig. 3 is a section on line III—III of Fig. 1, showing a bulb (in section) inserted in the socket.

Fig. 4 is a bottom plan view of the socket shell.

25 Fig. 5 is a side elevation of the same.

Fig. 6 illustrates a slightly modified form.

Fig. 7 is a plan view, showing a switch connection.

Similar reference numerals refer to like 30 parts throughout the specification and drawing.

The base 1 is of any suitable insulating material, as hard rubber, fibre, or asbestos board. The socket shell is of the usual general form as shown at 2, of cup shape with the spiral corrugation formed therein, into which the bulb ferrule may be screwed. The bottom of the shell 2 has the wide slot 3 cut diametrically across and up the sides for 40 some distance, as clearly shown. It also has the screw holes 4, 4, through which the small screw bolts 5, 5 are inserted, and by which the shell is secured to the middle of the base 1.

45 The contact spring 6 is fastened to the base 1 by the bolts 7, 7, and its free end extends through and beyond the slot 3 with its extreme end squarely bent in position to engage the head of the contact point 8.

50 When not engaging contact 8, spring 6 is dead, or de-energized. Leads 9 and 10 are provided, one from one of the bolts 5 to the binding post 11, and the other from the

contact 8 to the binding post 12, and from said posts circuit connections 13 and 14 are made with the source of electrical supply.

The usual form of bulb stem or shank is shown in section in Fig. 3. The glass envelop 15 has the re-entrant boss 16, through which the cathode rods 17, 18 are inserted, with the insulating cement C filling and surrounding the same, with the spirally corrugated ferrule 19 secured in place as shown. The cathode rod 17 is bent around and soldered to the ferrule, and the rod 18 is inserted into a metal button 20, which is embedded in the cement C. When the bulb is removed from the socket, the spring 6 will bear upon the edge of the slot 3, as shown in Fig. 2, and in dotted lines in Fig. 3, thereby breaking the circuit connection between the end of the spring and the contact point 8. But as the bulb is screwed down into the socket, the button 20 first makes contact with the spring and then forces the spring down until its bent end engages the point 8; so that the circuit is closed at a point completely outside of the socket and away from the button 20. When the bulb is unscrewed from the socket, the break occurs at the point 8, and never at the button 20. It will be noted also, that as the spring is arrested by the edge of the slot 3, the cathode rods 17 and 18 are short-circuited through the button 20, spring 6, shell 2 and ferrule 19.

The open bottom of the shell 2 permits air circulation about the point of contact between the button 20 and spring 6, and rapid dissipation of any excessive heat that may develop between the parts, while the removal of the arcing point completely outside of the shell completely overcomes the difficulty hitherto encountered in the usual form of bulb socket.

With slight changes in dimensions, without any change in general construction or operation, the device may be readily adapted for use as a lamp socket for the ordinary incandescent lamp. In the form shown, the parts are of comparatively heavy construction, which is necessary to the service required for rectifying A. C.

In the form shown in Fig. 6, the base 1, shell 2, glass envelop 15, and the construction of the parts of the bulb are the same as above described. For the spring 6, I substi-

- tute the pin 6', which passes through an aperture in the base and is held up by the spring 21. The cotter pin in the lower end of the pin 6' holds it against escape. On the underside of the base 1 is a rectangularly bent contact strip 8' secured in alignment with the pin 6', by the bolts 22. Leads 23, from the strip 8', and 24 from the shell holding bolt 5, connect the socket with an outside source of current. In this form of the invention the circuit make and break is between pin 6' and the contact strip 8', thus saving the button 20, as explained in connection with Figs. 2 and 3.
- In Fig. 7, I have shown all of the parts the same as in Fig. 1 with the exception that for the lead 10 between the contact 8 and the binding post 12, the small knife blade switch 10'' is substituted, with the pivot connection 10' located under the head of the contact 8, and the fork connection 12' mounted on the post 12. The occasion for the use of this form arises when it is desired to remove the bulb 15 while the current is on; the bulb is then so hot that it cannot be touched without burning the hand. It is only necessary to open the switch 10'', when the bulb will at once cool down and it can then be removed without danger of burning. The mounting of the switch upon the base 1 makes the entire structure self-contained, and obviates the use of an outside switch in the circuit for the purpose described.
- I claim:—
1. In a bulb socket, the combination of a 35 socket shell having a diametrical slot in the bottom thereof, an insulating base for said shell, a line terminal connected to the shell, a flat spring secured to said base by a dead end connection and extending through said 40 slot, and a contact point upon the said base, beneath the free end of said spring and adapted to be engaged thereby when the same is depressed by the insertion of a bulb into said shell.
  2. A socket connection, comprising a slotted shell, provided with a line terminal, an insulated resilient contact bar crossing said shell in spaced relation thereto, and a contact terminal adapted to engage one end of 50 said bar, in one position of the contact bar, and mounting means for the bar, whereby it engages the shell in another position.
  3. In a connector the combination of a 55 shell, a terminal connected to the shell, a terminal insulated from the shell, and insulated, terminal free means movable along the axis of the shell for making and breaking a circuit between said terminals, outside of said shell.

EARL H. ROLLINSON.
